UNITED STATES PATENT OFFICE.

WILLIAM G. KENDALL, OF NEWARK, NEW JERSEY.

COSMETIC-PAD HOLDER.

Application filed January 28, 1928. Serial No. 250,175.

This invention relates to an improved cosmetic pad holder, and a retaining ring, and has for an object to provide an improved structure wherein a pad may be properly held 5 in a holder or base and the base in turn properly held in a retaining ring or ring holder.

Another object is to provide a pad holder or plate, wherein the bottom is formed with indentations presenting retaining means for 10 holding a pad properly in the holder.

A still further object is to provide a pad holder or plate with a more or less corrugated circumferential flange and a pitted bottom.

An additional object is to provide a pad 15 holder retaining ring with a supporting flange and substantially resilient retaining means.

In the accompanying drawings—

Figure 1 is a plan view of a cosmetic pad 20 holder and retaining ring embodying the invention, the same being shown in connection with a vanity case indicated by dotted lines.

Figure 2 is a sectional view through the 25 retaining ring shown in Figure 1, the section being taken approximately on line 2—2 of Figure 1.

Figure 3 is a view similar to Figure 2 except that it shows a filled holder in connection therewith.

30 Figure 4 is an enlarged fragmentary sectional view.

Figure 5 is a plan view on a reduced scale of the holder shown in Figure 3.

Figure 6 is a plan view of a filled holder, 35 showing a modified form to that illustrated in Figure 5, part of the pad being broken away for illustrating the bottom formation.

Figure 7 is a sectional view through Figure 6 on line 7—7.

40 Figure 8 is a view similar to Figure 6, but showing a modified form of upstanding flange.

Figure 9 is a sectional view through Figure 8 on line 9—9.

45 Referring to the accompanying drawings by numerals, 1 indicates the body of a vanity case, and 2 the cover or lid. Arranged in the vanity case 1 is a retaining ring 3 sometimes known as a compact plate holder. This ring 50 is provided with a plurality of pressed in nibs or projections 4, which by reason of their formation as part of the vertical wall 5 of ring 3, present a somewhat resilient structure for pinching the holder or plate 6. A specially positioned holding nib or pressed out por-

tion 7 is provided substantially at the juncture of the wall 5 with the top plate or body 8 of ring 3. By positioning the pressed out portion, nib or ball 7 as shown in Figures 1 to 4 inclusive, the pressed out portion overlies 55 partially the upper edge of the holder or plate 6, thus materially assisting the nibs 4 in retaining the holder in the ring 3. It will also be noted that the ring 3 is provided with an inturned flange 9 which may be continuous 60 or interrupted, but which presents a supporting structure for the holder 6 so that the holder 6 need not rest on the bottom of the vanity case 1.

In many vanity cases, the bottoms are 65 curved more or less for ornamental purposes and, consequently, the holder 6 will not properly fit the same and, therefore, the ring 3 has been specially constructed so as to present a substantially Z-shaped formation in cross section, whereby the supporting member 9 is provided. In addition, the holder 6 is provided with a curved bottom 10 as shown in Figure 3, and a flat or horizontal section 11 near the periphery, said flat or horizontal 70 section resting on the flange 9. In this way the holder is held against tilting, while the retaining members 4 and 7 yieldingly and resiliently hold the holder in the ring.

As shown in the drawing, the holder 6 is 75 provided with an annular wall or flange 12 extending normally to the flange 9 and bent over at 13 for presenting a smooth upper edge and also for presenting anchoring means for anchoring the pad 14 in place. It is evident 80 that instead of having the turned over portion 13 as shown, and the flange 12 as shown, the upstanding wall could be merely inclined inwardly without any turned up portion or could be otherwise formed, though preferably 85 the same form of shoulder is desirable.

Instead of the holder shown in Figure 3, other forms of holders could be used, as for instance, those shown in Figures 6 to 9 inclusive. In Figures 6 and 7, a slightly modified form of holder is provided to that shown in Figure 3. In this form of holder, the upstanding wall 12' is formed with an inturned auxiliary flange 15, while the horizontal portion 9 is retained but the bottom 10 is pitted or formed with a plurality of depressed portions 16 which may be round or some other shape. By forming these depressed portions, shoulders 17 are provided at the junc- 100 105 110

ture between these depressed portions and the main part of the bottom 10. This formation assists the auxiliary flange 15 in retaining the pad 14' in place. The pitted portions 5 or depressions 16 may be uniformly arranged in any desired order, or may be scattered over the bottom in a miscellaneous manner. In either event, the same result is secured, namely, shoulder formations with which the 10 pad 14' interlocks.

In Figures 8 and 9, a further modified form of the invention is shown which is identical with that shown in Figures 6 and 7, except that the upstanding wall 12'' is formed with 15 an inturned portion 18 and also the wall 12' is provided with pressed out curved sections 19, thus presenting additional shoulder formations as well as a pleasing appearance to the holder. The bottoms 10 in these two 20 forms of the invention, have been shown arc-shaped except for the section 9, but if desired, flat straight bottoms could be used and the depressions 16 caused to function in the same desirable manner. When used in connection with the ring 3, the projections or 25 holding members 4 and 7 will properly operate in connection with flange 12'' and also usually with the pressed out portions 19, whereby the holder will be removably held in the ring and the ring in turn will be held 30 properly in the vanity case in any desired manner, usually by friction.

What I claim is:

1. A cosmetic pad holder and ring, comprising a substantially pan-shaped holder having an annular flat portion near the periphery, and a holding ring formed substantially Z-shaped in cross section, said ring being formed with means for yieldingly holding the flat portion of the holder against part 35 of said ring.
2. A cosmetic pad holder and ring, comprising a holder structure having an upstanding flange, said holder structure having a bottom 40 with a straight flattened portion near the periphery, and a ring for receiving said holder, said ring having a horizontal top plate, a depending flange extending normally of the top plate, and an inwardly extending flange 45 parallel with the top plate, said flange being

positioned to receive the flattened portion of said holder.

3. A holding ring for cosmetic pad plates, comprising an annular ring structure formed with a plurality of pressed out portions intermediate the top and bottom edges, and a pressed out portion at the top edge adapted to partially overlap said pad plate, said ring being formed with an annular top plate extending substantially at right angles to said 60 annular structure.

4. A cosmetic pad holder or plate, comprising a bottom formed with a plurality of depressed portions, and an upstanding flange formed at its upper edge with an inwardly 65 projecting portion.

5. A cosmetic pad holder or plate, comprising a bottom and an annular upstanding peripheral flange, said bottom having an annular straight flat bottom, and a curved portion, said curved portion being pitted. 70

6. A cosmetic pad holder or plate, comprising a bottom, and a circumferential upstanding flange, said flange being substantially corrugated for producing holding shoulders. 75

7. A cosmetic pad holder or plate, comprising a bottom and a peripheral upstanding flange, said flange having pressed out portions at spaced intervals for producing a substantially corrugated effect, the portions between the pressed out portions forming part 80 of a true circle.

8. A cosmetic pad holder or plate, comprising a bottom, and an upstanding peripheral flange, said flange having pressed out portions to present a substantially corrugated effect and said bottom having a flat section near the periphery, and a pitted section within the confines of the flat section. 85

9. A cosmetic pad holder or plate, comprising a bottom and an upstanding peripheral flange, said flange having a pressed-out portion presenting shoulders and said bottom having a flat section near the periphery and a pitted section within the confines of the flat 90 section.

Signed at New York in the county of New York and State of New York, this 26th day of January, A. D. 1928.

WILLIAM G. KENDALL.
